(57) CLAIM

The ornamental design for a power source housing element as shown and described.

DESCRIPTION

FIG. 1 is a front perspective view of a power source housing element in the form of an end plate;

FIG. 2 is a back perspective view of the power source housing element of FIG. 1;

FIG. 3 is a front view of the power source housing element of FIG. 1;

FIG. 4 is a back view of the power source housing element of FIG. 1;

FIG. 5 is a first side view of the power source housing element of FIG. 1;

FIG. 6 is a second side view of the power source housing element of FIG. 1;

FIG. 7 is a top view of the power source housing element of FIG. 1;

FIG. 8 is a bottom view of the power source housing element of FIG. 1; and,

FIG. 9 is a front perspective view of the power source housing element of FIG. 1 in the context of a full power source housing.

In the drawings, the dashed broken lines depict portions of the power source housing element and/or of a power source housing that form no part of the claimed design. Dot-dash broken lines depict a boundary of the claimed design.

1 Claim, 5 Drawing Sheets
